DESIGN FOR AN INSECT ELECTROCUTOR

Claude E. Canning, Wilmette, Ill.

Application July 8, 1935, Serial No. 57,566

Term of patent 7 years

To all whom it may concern:

Be it known that I, Claude E. Canning, a citizen of the United States, residing at Wilmette, in the county of Cook and State of Illinois, have invented a new, original, and ornamental Design for Insect Electrocutors, of which the following is a specification, reference being had to the accompanying drawing, forming part thereof.

In the drawing, the single figure is a front elevation of an insect electrocutor, showing my new design.

I claim:

The ornamental design for an insect electrocutor, as shown.

CLAUDE E. CANNING.
